Inventor:

Hans Grossmann,

By *Henry Orth*

Atty.

UNITED STATES PATENT OFFICE.

HANS GROSSMANN, OF ZURICH, SWITZERLAND.

LIGHTER.

Application filed June 2, 1922. Serial No. 565,450.

To all whom it may concern:

Be it known that I, HANS GROSSMANN, citizen of the Republic of Switzerland, residing at 28 Englischierviertelstrasse, Zurich, Switzerland, have invented certain new and useful Improvements in Lighters, of which the following is a specification, reference being had therein to the accompanying drawing.

The essential feature of the invention 10 consists in the combination of a receptacle as a storage device for combustible bodies provided with an ignitable composition all over, such as ignitable pellets, cubes, leaflets, etc. such storage device being provided 15 with a frictional surface for the combustible bodies and with means for holding the same while in use, and therefore for taking a combustible body from the storage device, for igniting the same and holding it while it 20 burns. The combustible bodies are conveniently withdrawn from the receptacle by means of a gripper and then ignited on any desired or a specially prepared frictional surface. After being ignited the combustible body then continues to burn in the gripper with a quiet flame, can be extinguished like an ordinary match or can be allowed to burn until exhausted. The residue left after combustion has taken place is 25 thrown away as in the case of an ordinary match. The gripper is replaced in the storage device or in the box for further use. The storage device and the gripper may 30 vary in form. The receptacle or the storage receptacle must be arranged, like the generally known match boxes, so that the separate combustible bodies can be easily withdrawn therefrom and that the unused ones cannot easily fall out during storage, 35 transport, or while being carried in the pocket. In the present case the storage receptacle for the combustible bodies may 40 consist of any desired material, it may be a rigid hollow chamber, so that the disadvantage of the match box manufacture, the fitting of a sliding drawer into an outer covering is done away with.

As a greater number of combustible bodies 50 can be in general contained in the storage device (receptacle) than was the case with ordinary matches, and as no sliding box is necessary as a receptacle, it is convenient to make both the receptacle and the grip-

per for the combustible bodies in a permanent form, so that when the receptacle is 55 empty it is only necessary to replace the combustible bodies consumed.

In the lighter according to the present invention the gripper for withdrawing, lighting and holding a combustible body may 60 with advantage consist of two parts movable relatively to each other with a spring placed between them, which tends to bring the two parts back into their original position. One part may conveniently form a sheath in 65 which the other moves longitudinally against the action of the spring and carries at the bottom an abutment for a combustible body to be seized and which is taken from the end of the other part projecting from the sleeve. 70 It is advantageous to provide the part which forms the sheath with a stop which serves to limit the travel of the part which moves in the sheath.

A number of constructional examples of 75 the subject matter of the invention are illustrated in the drawing.

Fig. 1 is a cross-section through the first constructional example of which

Fig. 2 is a plan partially in section. 80

Fig. 3 is a longitudinal section through a second constructional form of which

Fig. 4 is a plan partially in section.

Fig. 5 is a third constructional example, 85 of which

Fig. 6 is a plan.

Fig. 7 is a fourth constructional example in vertical longitudinal section, and

Fig. 8 is a horizontal section on the line 90 VIII—VIII of Fig. 7.

Fig. 9 is a plan in horizontal section of a fifth constructional example.

Fig. 10 is a longitudinal section of a detail of a gripper, of which

Fig. 11 is a plan. 95

Fig. 12 is a modification of a detail in section.

Fig. 13 is a modification of a detail of a gripper, in section, of which

Fig. 14 is a plan. 100

Fig. 15 is a plan of a sixth constructional form.

Fig. 16 is a section through a seventh constructional form.

Fig. 17 is a vertical longitudinal section 105 through the first constructional example.

Fig. 18 is a horizontal section on the line II—II of Fig. 17.

Fig. 19 is again a vertical longitudinal section, but in a different position.

5 Fig. 20 is a second constructional form in vertical longitudinal section, of which

Fig. 21 is a horizontal section on the line V—V of Fig. 20, and Fig. 22 is a vertical section on the line VI—VI of Fig. 20.

10 Fig. 23 is a modification of Fig. 22.

Fig. 24 is a plan of Fig. 23, and

Fig. 25 is a further constructional example in perspective.

15 Fig. 26 is still another constructional example partially in section.

In Figs. 1 and 2 the combustible bodies which form the ignitable pellets are introduced into a sliding box 1, 2, in which the sliding part 2 is movable in the cover 1 which is open at both ends. In the sliding part 2 a supporting surface 3 forming a guiding device for a pair of tweezers 4 is attached to a longitudinal wall by an adhesive for example. This supporting surface 3 for the tweezers 4 is situated at such a distance from the bottom of the sliding part 2 that sufficient space is left between the said supporting surface 3 and the part 5 of the cover 1 to enable the tweezers to be conveniently pushed in. There is no room for the combustible bodies i. e. the ignitable pellets. In Figs. 1 and 2 the tweezers 4 are provided with a bead-shaped enlargement 6 at one end, which prevents them from being pushed completely into the box. When the box is closed this bead 6 projects a few millimetres from the box and permits of their being easily laid hold of without having to feel about for them. After having been used the tweezers can be readily pushed into the box again between the cover 1 and the supporting surface 3. The available space in the box is only slightly reduced in actual practice by the provision of the above described supporting surface. As there is risk of the separate combustible bodies falling out of the box when it is opened owing to the movement of the sliding part 2, it is more suitable to construct the box as shown 50 in Figs. 3 and 4.

In Figs. 3 and 4 a cover only is provided, which is closed at both ends by flaps 7, and the supporting surface 3 which forms the guiding device for the tweezers 4 is affixed 55 to one of the side walls. In the top of the cover 1 is provided an opening which permits of the insertion of the tweezers and the withdrawal of the ignitable pellets. To enable these latter to be withdrawn the guiding device 3 is made shorter than the box 1. By this means a small hollow space 9 is provided between the end wall 8 and the guiding device 3, in which the little balls can collect by tilting the box and can then be 60 easily withdrawn by means of the tweezers.

This hollow space 9 might also be of such a depth that there is room for only a single ignitable pellet. By pushing in the tweezers this opening 10 in the top of the cover 1 is closed so that it is impossible for the ignitable pellets to fall out either during transport or storage or into the pocket. The advantage of this constructional form is that the box need not have any movable parts.

70 The constructional form illustrated in Figs. 5 and 6 shows that the tweezers 4 need not be carried in the box itself but may surround it like a clamp, but close the opening 11 for the withdrawal of the pellets at the same time.

75 Figs. 7 and 8 show a constructional form in which the receptacle for the ignitable pellets is made in two parts, the parts 12 and 13 being attached to each other by being joined together, by an adhesive for example. These two parts 12 and 13 are made quite symmetrically, but might also be asymmetrical. The formation of the receptacle in two parts enables it to be made of all kinds of shapes. The receptacle 12, 13 has an opening 14 in it for the introduction of a pair of tweezers 15, which are automatically held in the said opening 14 by their 80 spring action. In order that the tweezers 15 shall not be pushed too far into the hollow space in the receptacle 12, 13, stops 16 are provided which leave just sufficient room between them for one ignitable pellet and to allow of its being seized by the tweezers. If the receptacle is only partially filled with combustible bodies, a pellet can easily be brought within reach of the claws of the tweezers by shaking the receptacle.

85 As shown in Fig. 9, there may also be provided in the interior of the receptacle a selector device 17, for the pellets, which device is arranged close to where the tweezers 18 are introduced opposite the opening 19. This selector device 17 enables a single 90 pellet to be separated from the others and brought opposite the opening for the introduction of the tweezers 18, so that when the latter are introduced the pellet can be seized thereby. These tweezers 18 consist of a 95 sheath with claws 20 which are adapted to seize the pellet. In this sheath is mounted a longitudinally movable pusher 21, so that the burnt out pellet can be ejected from the claws.

100 The pusher might also co-operate with a spring in the interior of the sheath, so that when the burnt out pellet has to be ejected the force of the spring has to be overcome and the spring automatically returns the 105 pusher to its position of rest.

110 As shown in Figs. 10 and 11, the tweezers for the pellets may be conveniently constructed as a clamp 22 with claws 23. The clamp is itself elastic.

Between the claw 23 of each limb of the clamp is formed a slot 24 which acts as a ventilating device, so that the air may be afforded access all around the pellets in order not to hinder the combustion of the pellet held in the claws of the clamp.

The tweezers may also be provided with a stop 26, which prevents the splaying of the limbs of the clamp, as shown in Fig. 12, so that when introduced into the opening of the receptacle 26 it may not be thrust too far into the interior of the latter. An abutment for the stop 26 may be provided by the mouth of the opening in the receptacle or by a projection in the mouth thereof as shown.

In order to render it unnecessary to keep the clamp compressed by the fingers after a pellet or a combustible body has been seized thereby a slide 27 may be arranged over both limbs of the clamp as shown in Fig. 12. When this slide is moved towards the claws of the clamp the two limbs of the tweezers are compressed owing to their slightly conical shape, and the tweezers with the burning pellet, handed over to another person without the two limbs of the tweezers having to be kept pressed together.

As shown in Figs. 13 and 14, the tweezers 28 may also be provided with two claws on one limb between which claws a claw on the other limb engages, thereby causing the claws to interlock. By pressing the two limbs together both ends thereof are caused to open and a combustible body can then be seized and is firmly held when the pressure between the three claws 29 ceases. Access of the air to the pellet is ensured in this case also.

In the above described constructional examples the combustible bodies are freely movable in a receptacle in each case.

It is also possible however, to arrange the combustible bodies rigidly in a storage device, as shown in Fig. 15. In order to cause these combustible bodies to ignite, the carrier 29 for the pellets 30 has a recess 31, into which a striking device 32 provided with a frictional surface projects. When this striking surface 32 is withdrawn and moved along a pellet 30, the latter is caused to ignite. The apparatus is also so arranged, that the adjoining pellet shall not become ignited. The form of the carrier may be any that may be desired.

It is also possible, as shown in Fig. 16, to arrange the several combustible cores 33 in a carrier 34, which is provided for this purpose with as many hollow spaces as there are combustible cores for the carrier to contain. This latter has also an opening 36 which serves for the reception of the tweezers 37 for the pellets. This opening is so constructed that by simply placing the tweezers therein they are held in place by a clamping action. Each combustible body is

thus firmly held in its own compartment and can be easily seized and withdrawn therefrom by the tweezers 30.

The tweezers of rigid material, a form of which is shown in Fig. 9, may likewise be coated with means for protecting them from heat. The pincers and tweezers may also be made of rigid material in two parts, connected together by means of a hinge and provided with an auxiliary spring. If an ejecting device be provided for the burnt out pellet or for the residues, it may consist of metal or some other material. The ejector may be held in position by simple friction in the tweezers and be operated by the pressure of the fingers. When the tweezers are provided with a slide passing over both limbs thereof this slide may also act upon a projecting bead on the limbs so as to keep them pressed together so that the combustible body is simultaneously gripped between the claws of the tweezers. When the slide is opened or pushed back the burnt out combustible body can at once drop out of the claws of the tweezers.

The tweezers may also be carried on the outside of the storage device or receptacle, being pushed into a guide, a groove or the like. By this means space for the combustible bodies or pellets in the receptacle is gained.

Instead of the constructional form shown in Fig. 9, the receptacles for the combustible bodies may also be provided with a guide which automatically supplies the pellets to the tweezers by a simple movement and which in consequence always permits only one pellet to pass through. This guiding device for the pellets serves also as a storage chamber for the tweezers.

The frictional surface may naturally consist of a safety composition or any desired kind of rough surface.

The constructional form shown in Figs. 17, 18 and 19 has a receptacle for the single combustible body 30 and from its uppermost edge a wall 43 projects downwards but not right to the bottom of the receptacle 41. This wall 43 leaves just sufficient space between its lower edge and the bottom 44 of the receptacle 41 for a combustible body to pass through, which however it is prevented from doing by a spring 45 which is fixed to the bottom and bent up against the lower edge of the wall 43. This latter separates a passage 46 from the receptacle which is open at the top and into which a pair of tweezers is introduced. This pair of tweezers has a sheath 47 in which a part 48 is movable by overcoming the tension of a spring 49. The lower end of the sleeve 47 is bent into the form of a hook and this end 50 acts as an abutment for a combustible body to be seized. The part 48 projects with its lower end from the sleeve 47 below and

forms a double claw 57, sufficient space being left between both claws for the supply of air which is required for combustion of the combustible body. The part 48 is produced by being bent up from a strip of metal and the other free end of this strip is bent into a hook, which, between the upper end of the spring 49 and a stop 53 in the sleeve, serves to limit the longitudinal movement of the part 47. This stop 53 can be formed by a pin or a projection in the sleeve or the like.

The receptacle 41 may consist of metal, cardboard or paper in one piece or of metal with a movable cover as shown in Fig. 18, where the cover 54 is hinged on. This has a frictional surface 55 in a recess 56 in the side wall of the receptacle 41.

When the combustible bodies are in the receptacle 41 and it is desired to ignite one, the part 48 of the tweezers is pressed into the passage 46 or into the sleeve 47, the spring 45 being pressed against the bottom 44 of the receptacle 41. By this means a combustible body can roll under the lower end of the wall 43 and be brought into the double claw 51. When the sleeve 47 is withdrawn from the passage 46, the combustible body will be firmly held between the abutment 50 and the claw 51. The protecting spring 45 however at once shuts off the opening 48 under the lower end of the wall 43 when the pressure is relaxed. By relaxing the pressure on the part 48 of the gripper the combustible body is then held between the jaws of the tweezers (the double claw 51 and abutment 50) as the position of the jaws of the tweezers is such that they adapt themselves to the size of the pellet-shaped combustible body. When the tweezers are withdrawn the spring 49 keeps the pressure up longitudinally of the tweezers in the pellet so that it cannot fall out of the jaws. The ignition of the pellets in the tweezers is produced by rubbing the head of the ball protruding from the jaws of the tweezers. By means of this arrangement combustible bodies which become soft when they burn can be used. The pellet is not compressed but is yet firmly held by the pressure which retains it. After use pressure is applied to the movable part 48 of the tweezers and the burnt out remains fall at once, or by the aid of a straight tap, out of the tweezers. The latter firmly holds the pellet which softens while it burns, but does not crush it, which is important for the easy removal of the burnt out remains from the tweezers.

Fig. 20 shows a pair of tweezers in which a portion 58 shaped like a pair of tongs is longitudinally movable in the sleeve against the action of the spring 59. A stop 60 is provided in the sleeve 57 and the spring 59 bears against this stop. The lower end of the sleeve 57 carries a locking bridge 61, which

prevents the combustible bodies seized from rolling into the interior of the sleeve 57, but yet allows the bridge sufficient room at its side for the jaws 62 of the tweezers to pass through. These jaws 62 open under pressure applied to the top of the part 58, the spring 59 being compressed. This latter moves the tongs-shaped part 58 upwards again, when the pressure on the part 58 is relaxed. In order that the tweezers shall not fall out of the receptacle 41, the upper edge parts of the sleeve 57 are elastically bent over, so that they can hold firmly on the side walls of the receptacle 41. By slightly inclining the receptacle 41 a combustible body can be brought exactly under the tweezers and seized by the jaws 62 thereof when the part 58 is depressed. The ignition of the combustible body seized is produced by rubbing it on the frictional surface, which in the present case is firmly held between the cover and the side walls of the receptacle 41. In this case also the tweezers are placed or held in a passage divided off by a division wall 43. Again in the present case the size and the position of the jaws of the tweezers and the action of the spring is so arranged, that the pellet shall be securely held, but is prevented from being crushed while burning.

In the case of pellets which have a hard core when they burn the adjustment is considerably more simple. By applying pressure to the part 58 of the tweezers after the pellet has been ignited and used the jaws of the tweezers are moved apart owing to their construction and the burnt out pellet at once drops out of the claws 62 of the tweezers. In this case also the jaws grasp the pellet so that the lower spherical surface thereof remains free and can be rubbed without hindrance on an igniting or frictional surface. Again in this case the receptacle can be made in an extremely simple form, e. g. out of pieces of wood, cardboard, paper, etc. To prevent the tweezers from falling out of the receptacle and to avoid too accurate a construction of the receptacle, two or only one overlapping portion is provided at the upper end of the tweezers sleeve, which overlapping portion 64 catches easily and elastically over the walls of the receptacle. This form of the tweezers can naturally also be used in the case of the receptacle shown in Fig. 17.

Instead of making the tweezers of the same width as the receptacle 41 itself, it is also possible in wider receptacles to provide in one corner a rectangularly bent up partition 65 as shown in Fig. 24. In other respects the construction of the tweezers shown in Figs. 23 and 24 is the same as in Figs. 20, 21 and 22.

It is not necessary that the tweezers should be contained in the receptacle itself, on the

contrary the tweezers may also be kept separate from the receptacle for the combustible bodies. This is advisable in cases where the bodies are always ignited in the same place, as in a kitchen for example. The pellets are kept in a receptacle 66 and a number of frictional surfaces are provided thereon in the form of a block with single leaves which can be torn off like a tear-off calendar, which block 67 is arranged at the side of the receptacle 66, but might also be hung up separately therefrom.

In Fig. 20 the frictional surface is held in place by being simply clamped between the lid and the receptacle and removed by lifting up the lid; and the receptacle may be piled with combustible bodies at the same time. A metal plate 63 for stiffening the frictional surface may also be inserted underneath it as shown in Fig. 18.

The tweezers shown possess the following properties: they permit of each single combustible body being securely and easily grasped, when ignited; and while burning it is only possible for the pellet to fall out under extraordinary circumstances. After use the burning, extinguished or used up combustible body can be removed by a simple movement; and by a simple movement in the receptacle the next pellet can be simultaneously seized and prepared for the next ignition.

With the constructional form shown in Figs. 17, 18 and 19 in which a separate receptacle for the single combustible body is provided in which receptacle the gripper is inserted, the latter and combustible bodies may fall out of the receptacle when the gripper is removed from the latter, i. e. when the gripper is utilized for lighting a pellet.

These disadvantages are overcome by the constructional example illustrated in Fig. 26. In a receptacle 70 having a rectangular cross-section in a plan view combustible bodies 71 in the shape of little spheres i. e. the ignition pellets, are contained. In this receptacle a plate spring 72 is so inserted that an oblong channel is formed adapted to take up the gripper 74. This plate spring is secured with its one end to one of the short sides of the receptacle by means of a folded portion 73. The other end of this spring is so bent that when the gripper 74 is partly or totally withdrawn the passage is closed by the end of the spring, as shown in Fig. 26. From the rear wall of the receptacle 70 a small portion is bent to project into the interior of the receptacle, this portion 79 serves as a stop for the spring 72. The receptacle is closed by means of a sliding lid 73, the upper edge 78 of which being provided with a folded over portion into which the frictional surface 76 for igniting the safety ignition pellets thereon is inserted. In connection with the folded portion 78 the

other three sides of the receptacle 70 are provided with similar folded portions 77 adapted to form a guidance for the sliding lid 75 and to hold the frictional surface 76 in position.

The gripper 74 consists of a sheath having a square cross-section and a tapering lower end 84 made by cutting at the four sides oblong portions out of the sheath and pressing the remaining portions together. Four apertures 85 are thereby formed in this tapering end portion of the gripper which act together with the end portions as flues for permitting access of air. Within the sheath two U-shaped steel wires 80 are crosswise arranged which project above the sheath and are connected together, for instance by soldering, at the uppermost point where they cross each other. The four free ends of the two steel wires 80 project beyond the lower tapering part 84 of the gripper 74 and are adapted to grip or clamp an ignition pellet in the manner shown in Fig. 26 of the drawing. The sheath of the gripper is transversed by a pin 82 upon which a helical spring 81 rests, the latter tending to lift the two steel wires 80 and to pull the claw-shaped ends of the latter into the tapering portion 84 of the sheath. A pressure exerted on the steel wires projecting above the sheath causes the spring 81 to be compressed whereupon the free ends of the two steel wires move further out of the tapering portion 84 and spread out in order to be able to clamp the ignition pellet present at the lower end of the passage formed by the plate spring 72.

When the gripper 74 is inserted into the passage it is frictionally engaged by the spring, whereby the gripper is prevented from falling out. When the gripper is pushed into the passage until the wings 83 rest on the upper edge of the receptacle, the lower end of the spring 72 is pushed aside by the tapering portion 84 of the gripper so that the passage is opened at its lower end and a pellet which is in the corner of the receptacle may be engaged by the gripper.

With the gripper in this position a pressure on the steel springs projecting above the sheath, whereby the power of the spring 81 has to be overcome, causes the free ends of the steel wire to project further beyond the lower end of the tapering part 84 and to clamp the pellet placed within reach. As soon as the pressure relaxes the claws retreat somewhat and clamp the pellet tightly. When the gripper is now withdrawn from the passage it holds a pellet. The withdrawing of the gripper is facilitated by the wings 83 provided on the gripper 74. The passage is automatically closed by means of the plate spring 72 so that no further pellets can fall out of the receptacle 70 when the gripper is removed.

The gripped ignition pellet may then be lighted at the frictional surface 76. When the gripper is held with the burning pellet pointing upwards a sufficient supply of air to the pellet is provided by the apertures 85 and the tapering portion 84 which act similar to a chimney. The steel wires 80 are comparatively thin, they absorb therefore little heat and cover only a small portion of the surface of the pellets, so that the ignition is not hindered by same. The pellet burns quietly.

The tapering end of the gripper enables an easy insertion of the latter into the passage also in the dark. By withdrawing the slide 75 the receptacle may conveniently be filled with pellets and the frictional surface may be replaced by a new one. Instead of being made of metal the receptacle might be folded of one piece of cardboard. In the lower part of the wall of the receptacle a window may be provided for controlling the contents. The stop 79 in the rear wall of the receptacle may be made longer so that an oblong slot is formed in said wall through which the contents may be controlled.

The lower end of the plate spring 72 may be bent so that a supply passage is formed for containing several pellets, whereby the bent off portion of the plate spring is arranged parallel to the lower wall 70 of the receptacle when the spring closes the lower end of the passage containing the gripper. Thereby it is ensured that one pellet is in the corner of the receptacle below the gripper. The tapering end 84 of the gripper ensures a good guide of the two clamping wires 80.

I claim:

1. A lighter comprising in combination an apertured receptacle adapted to hold combustible pellets completely surrounded by an ignitable composition, means on said receptacle forming a chamber registering with said aperture in which chamber said pellets are singly presented to said aperture, tongs consisting of two relatively movable parts and a spring placed between them, one of said movable parts being a sleeve in which the other part is longitudinally movable against said spring, a single pellet being gripped by the relative movement of said tongs parts for withdrawing a pellet, holding the withdrawn pellet during ignition and while it burns, said tongs being normally inserted in said chamber and covering said aperture.

2. A lighter comprising in combination an apertured receptacle adapted to hold combustible pellets completely surrounded by an ignitable composition, a movable cover on said receptacle and provided with

an interchangeable frictional surface, a partition wall consisting of a plate spring in said receptacle forming a chamber registering with said aperture in which chamber said pellets are singly presented to said aperture by passing under the plate spring, tongs having claw shaped ends adapted to grip a single pellet for withdrawing the latter, holding the withdrawn pellet during ignition and while it burns, said tongs being normally inserted in said chamber and covering said aperture, said plate spring holding said tongs securely in position when inserted and causing the lower end of the chamber to be closed when the tongs are withdrawn.

3. A lighter comprising in combination an apertured receptacle adapted to hold combustible pellets completely surrounded by an ignitable composition, a movable cover on said receptacle and provided with an interchangeable frictional surface, a partition wall consisting of a plate spring in said receptacle forming a chamber registering with said aperture in which chamber said pellets are singly presented to said aperture by passing under the plate spring, tongs consisting of two relatively movable parts and a spring placed between them, one of said parts having claw shaped pellet receiving ends adapted to grip a single pellet by the relative movement of said tong parts for withdrawing a pellet, holding the withdrawn pellet during ignition and while it burns, said tongs being normally inserted in said chamber and covering said aperture and being securely held in position when inserted by said plate spring, the latter causing the lower end of the chamber to be closed when the tongs are withdrawn, the lower portion of said tongs being tapered in order to provide for a more convenient insertion into said chamber and to provide for apertures permitting of access of air in said tapered portion of the tongs to the ignited gripped pellet.

4. The combination in a match pellet receptacle having an aperture, of a plate spring in said receptacle forming a partition wall and forming with said receptacle means for frictionally holding a pellet remover, a pellet remover comprising clamping jaws capable of engaging the pellet from the top when projected into said aperture, said pellet remover covering the aperture and filling the space between one side of said spring and receptacle, and said spring automatically and fully closing to pellets the chamber formed between the spring and receptacle as the pellet remover is withdrawn.

In testimony whereof I affix my signature.

DR. HANS GROSSMANN.
